INVENTOR

BY *Victor J. Evans*

ATTORNEY

UNITED STATES PATENT OFFICE.

JOHN M. ROLL, OF CORRECTIONVILLE, IOWA, ASSIGNOR OF ONE-HALF TO CARL JACOBS AND ONE-FOURTH TO E. E. JACOBS, BOTH OF CORRECTIONVILLE, IOWA.

TIRE-TREAD-REMOVING DEVICE.

1,393,576.

Specification of Letters Patent. Patented Oct. 11, 1921.

Application filed August 14, 1920. Serial No. 403,587.

To all whom it may concern:

Be it known that I, JOHN M. ROLL, a citizen of the United States, residing at Correctionville, in the county of Woodbury 5 and State of Iowa, have invented new and useful Improvements in Tire - Tread - Removing Devices, of which the following is a specification.

This invention relates to a device for 10 moving treads from tires and relates more particularly to my co-pending application Serial No. 393,717 filed July 2, 1920, and has for its primary object the construction of a device of few parts substantially associated 15 and which may be manufactured at a relatively low cost without sacrificing the efficiency thereof.

An object of the invention is to form the 20 blades and the rim portion of the wheel solid and case hardening blades so that same may be properly sharpened and will perform the necessary work required.

Another object of the invention is the 25 novel manner of constructing and associating the various parts so that they may be independently constructed at a reduction in the cost of manufacture and which may be quickly assembled.

With these and other objects in view the 30 invention will be better understood from the following detailed description taken in connection with the accompanying drawing wherein:

Figure 1 is a side elevation of the device.

Fig. 2 is a vertical sectional view.

Fig. 3 is a side elevation of one of the disks.

Fig. 4 is a fragmentary view of a portion of the wheel.

Fig. 5 is a similar view of a modification.

Again referring to the drawing illustrating one of the many constructions of my invention the numeral 1 designates the rim portion of the wheel in the form of a ring 45 having inwardly projecting lugs 2 each provided with a hole 3 for the purpose herein-after described. This ring has formed integral therewith a number of blades 4 each formed to have an inclined upper surface 50 5 and an inclined under surface 6 so that the cutting edge 7 will be spaced a predetermined distance from the surface of the ring. In practice these blades are hardened in any suitable manner so as to increase the

wearing qualities thereof and to insure a 55 sharp cutting edge. The numerals 8 and 9 designate a pair of disks, each provided with a hub section 10, and disk 8 is further provided with a conical extension 11 fitting in a tapering recess 12 in the other disk and 60 thus in a substantial manner I provide a hub for securing the wheel of a drive shaft. The blades are secured together and to the lugs 2 by the bolt 13.

By this construction it will be seen that 65 the parts may be readily separated by removing the blades and may be assembled very quickly at very little expense.

A feature of the invention is the novel manner of constructing and arranging the 70 blades so that they may be sharpened from time to time without necessitating the removal of the blades.

Another feature is forming the blades 75 as illustrated so that their position is permanently fixed and cannot become dislocated in any portion of the wheel thereby insuring accurate operation of the blades upon the tread of a tire.

In Fig. 5 I have shown the blades provided with an arcuate shape cutting edge 14 so as to increase the cutting operation.

From the foregoing description taken in connection with the accompanying drawing it will be apparent that I provide a cutting 85 wheel of very substantial construction in which the parts are associated in such a manner that they may readily be connected and disconnected with the additional advantage that the blades are permanently 90 fixed and may be readily sharpened when necessary.

It is, of course, to be understood that the invention may be constructed in various other manners and the parts associated in 95 different relations and, therefore, I do not desire to be limited in any manner except as set forth in the claims hereunto appended.

Having thus described my invention what 100 I claim is:

1. A tire tread removing device comprising a ring having integral cutting blades projecting therefrom, having disks bolted to the ring and each provided with a hub extension.

2. A tire tread removing device comprising a one piece ring, blades formed integral

therewith and projecting from the outer periphery of the ring, and hub disks detachably secured to the ring.

3. A tire tread removing device comprising a ring, blades formed integral with the ring and projecting therefrom to provide an inclined under surface and an inclined upper surface, and disks detachably bolted to the ring, each of said disks being formed

10 with a hub section and one having a conical

extension engaging in a recess in the other disk.

4. A tire tread removing device comprising a ring formed with a plurality of blades and having inwardly projecting lugs, and 15 upper disks bolted to the lugs, and each having a hub section.

In testimony whereof I affix my signature.

JNO. M. ROLL.
